UNITED STATES PATENT OFFICE.

ADOLPH H. REIMANN, OF DETROIT, MICHIGAN.

CURTAIN-GUARD FOR WINDOWS.

1,389,843.

Specification of Letters Patent.

Patented Sept. 6, 1921.

Application filed February 10, 1920. Serial No. 357,635.

To all whom it may concern:

Be it known that I, ADOLPH H. REIMANN, a citizen of the United States of America, residing at Detroit, in the county of Wayne 5 and State of Michigan, have invented certain new and useful Improvements in Curtain-Guards for Windows, of which the following is a specification, reference being had therein to the accompanying drawings.

10 When a window over which inside curtains of lace or other thin material are hung, is opened, the draft created will usually carry the lower free ends of such curtains out of the window or against the outside window 15 screen. These curtains thus quickly become soiled and worn. The object of this invention is to provide simple, cheap and efficient means for preventing such curtains from being carried out of the window or against 20 the dirty outside screen by drafts or breezes of air when the window is open, and to also provide means for the purpose which will not obstruct the view, be noticeable from the outside, or interfere with the closing of the 25 window. A further object is to so construct and arrange a device for the purpose that the window may be closed in the usual manner and such device will be automatically operated or swung out of the way and may be 30 readily again swung into operative position when the window is opened.

With the above and other ends in view, the invention consists in the matters hereinafter set forth and more particularly pointed out 35 in the appended claims, reference being had to the accompanying drawing in which—

Figure 1 is a perspective view of a device embodying the invention and showing the same in operative position upon a window 40 frame;

Fig. 2 is a transverse section through a window frame showing the device in operative position thereon;

Fig. 3 is a sectional detail of the device;

Fig. 4 is an elevation of the same with parts broken away and in section, one of the arms being removed; and

Fig. 5 is a similar view showing both arms in elevation and one member of the clip 50 broken away.

In the drawing, A indicates a window frame of the usual construction, B the lower sash and C the upper sash of the window. Suitable clip or pivot members 1 are secured

to the window frame at each side thereof and 55 are preferably located outside of the plane of the vertical movement of the outside sash C, said clips each comprising superposed plates 2 and 3 secured to the casing by screws 4 passing through alined holes in the plates, 60 and the plate 3 being offset near its lower end from the lower end of the plate 2 to provide a space between said ends to receive the ends of parallel arms 5 and 6 which are pivotally attached thereto by a pivot pin or 65 rivet 7 passing through alined openings in the ends of the plates and arms. Preferably, a washer 8 is interposed between the arms 5 and 6 and the offset of the plate 3 is less than the combined thickness of the 70 arms and washer so that when the screws 4 are turned down, they will draw the plates together and clamp the arms between the plate 2 and the off-set end of the plate 3 to frictionally hold the arms against turning 75 upon their pivotal connection.

Two pairs of pivotally connected and supported arms are thus provided, one pair at each side of the window casing and preferably positioned opposite the lower sash B 80 midway thereof to swing inwardly through the open window when the lower sash is up as shown in Figs. 1 and 2. The inner ends of like arms of each pair, are connected by suitable cords, wires or the like indicated 85 at 9. When these connected arms are swung inwardly, the upper arm engages a stop 10 on the window frame to hold the upper arm in a substantially horizontal position and the inward turning movement of these upper 90 arms carries the lower arms inwardly by means of a lug 11 on the pivoted ends of the arms 6 adapted to engage a flattened or cut away portion 12 of the arms 5. When thus positioned with the pairs 95 of arms extending inwardly through the open window, the cords 9 are held in a position to be engaged by the window curtain and thus prevent the curtain from being blown outwardly through the window. The 100 arms are spaced apart and thus the cords are held in a horizontal position and in spaced relation so that the lower end of the curtain will be prevented from being carried out through the window around the upper 105 cord.

When the sash B is lowered it will come in contact with the upper arms and swing the

arms downwardly out of its path so that it may be closed without the necessity for operating the device by hand. When the window is opened and it is desirable to again swing the device into operative position, this may be done by grasping the upper arms and swinging them inwardly, and by reason of the lugs 11 the lower arms will be automatically moved to their proper position.

10 Obviously other means than the plates 2 and 3 may be provided for pivotally attaching the arms to the window casing and for creating a frictional engagement with the arms to hold them in the position to which they are adjusted. It is also obvious that the form or construction of the arms may be changed to suit the conditions under which they are to operate and that the device may be applied to any window casing. It is also obvious that upon small windows where only a single cord is necessary in order to prevent the curtain from being blown out of the window, a single arm may be employed at each side of the casing, and other changes 20 in the form and construction of the parts may be made within the scope of the appended claims, without departing from the spirit of the invention.

25

What I claim is:

1. In a device of the character described, 30 the combination of opposed arms, means for pivotally attaching each arm to a window casing comprising a pair of members between which one end of the arm is pivotally supported and means for securing the members 35 to a window casing and for drawing the same into frictional contact with the arm, and a cord connecting the free ends of the arms.

2. In a device of the character described, the combination of arms arranged in pairs, 40 means for pivotally connecting the arms of each pair and for attaching the same to a window casing, one of the arms of each pair being formed with a lug to engage a cutaway portion of the other arm to cause the arms 45 to turn together and to provide a limited relative turning movement, and cords connecting the free ends of like arms of the pairs.

In testimony whereof I affix my signature 50 in the presence of two witnesses.

ADOLPH H. REIMANN.
